UNITED STATES PATENT OFFICE

HAROLD I. DANZIGER, OF NEW YORK, N. Y., ASSIGNOR TO CONDENSER CORPORATION OF AMERICA, OF JERSEY CITY, NEW JERSEY, A CORPORATION OF NEW YORK

ELECTROLYTIC CONDENSER

Application filed March 13, 1931. Serial No. 522,251.

My present invention relates generally to electrical condensers, and has particular reference to improvements in condensers of the electrolytic type.

5 The type of condenser to which my present invention appertains is of the general character disclosed in my co-pending application Serial Number 439,578, filed March 28, 1930, and consists briefly of an electrolyte container, usually of substantially cylindrical shape, and an electrode or electrodes immersed within the electrolyte and provided with means on the exterior of the container for establishing electrical connections thereto.

10 In condensers of this general character, it is desirable, if not essential, to provide means for venting the interior of the container, and, more especially, the upper portion thereof, so that the gases which are present above the 15 level of the electrolyte and which may under certain circumstances develop pressures beyond a predetermined safe or desirable maximum may have an opportunity to escape in part so as to relieve the excessive pressure.

20 Before proceeding to describe the details of my present invention, I will premise that a mere aperture or opening in an upper wall of a container, although serving to permit such venting, is, from many aspects, unsatisfactory for the reason that the interior of the 25 container would then be open to the atmosphere at all times, and for the further reason that packing, shipment, and handling of the condenser would be interfered with by the

30 likelihood of leakage through such aperture of the electrolyte. Where the venting aperture is provided in a protuberance adapted to accommodate a cap, the cap being, for example, of relatively soft, resilient material 35 such as rubber and provided with a pinhole which is normally closed but which opens under excessive pressure conditions, many disadvantages frequently result. For example, the projecting nature of such a venting ar-

40 rangement increases the likelihood of accidental encounter therewith with the possibility of damage; the cap may, under certain circumstances, come off unless special precautions are taken to keep it in place; the 45 exposure of a protuberance with or without

a cap is not conducive to attractive nor workmanlike appearance; and the construction and assembly of such devices, of necessity, require special procedures, tools, and precautions.

55 Similarly, although a venting arrangement of the foregoing character may, under certain circumstances, be expeditiously provided at the central portion of a substantially circular top wall of a container, it is relatively more difficult and inexpedient to provide such an arrangement at an eccentric position.

60 It is a general object of my present invention to provide an improved venting arrangement for a structure of the foregoing general character, and, more particularly, to provide a device which is in its entirety disposed within the container itself, whereby 65 external protuberances are entirely dispensed with.

70 It is a further object of my invention to provide a device which requires no protuberances whatsoever, either exteriorly or interiorly, and which is composed of relatively simple and inexpensive parts and instrumentalities which produce a staunch and workmanlike finished structure and which are relatively inexpensive and simple from a manufacturing and assembly standpoint.

75 My present invention is of particular value 80 in connection with structures wherein the operative portions of the condenser structure project outwardly through the top of the device, as, for example, in the case of an electrode-supporting rod which extends upwardly through the top wall of a substantially cylindrical condenser, because, in such an event, the absence of any additional projections improves the appearance and general 85 efficiency of the construction both from the standpoint of manufacture and of reliable and rugged performance.

90 It is a particular feature of my invention 95 to provide an arrangement wherein a wall of the container is provided with an aperture adapted to serve as a vent, and wherein means are arranged within the container for normally sealing said aperture and for unsealing it only at those special times at which escape 100 of gases or relief of pressure is to take place.

Briefly, my invention resides in the provision of such an aperture, in combination with a specially constructed valve arrangement in the interior of the container and adjacent to the aperture.

In a preferred construction, the valve includes a movable diaphragm, for example, a diaphragm or web of relatively soft, resilient, distendable material such as rubber, the diaphragm serving normally to rest in a retracted position wherein the vent is closed or sealed, and the movement, as, for example, the distention, of the diaphragm serving under predetermined conditions to unseal the vent.

Where an operative portion of the condenser structure extends through a wall thereof, as for example, where an electrode-supporting rod extends upwardly through the top wall of a container, I prefer to mount the valve arrangement on this rod itself, thereby facilitating manufacture and assembly and producing a compact and rugged construction which is highly efficient.

I achieve the foregoing objects and advantages, and such other objects and advantages as may hereinafter appear or be pointed out, in the manner illustratively exemplified in the accompanying drawing, in which—

Figure 1 is a cross-sectional elevation of a condenser of the present character embodying the features of my present invention and shown in mounted relationship upon a supporting platform or the like;

Figure 2 is an exploded view of the upper portion of the condenser with parts omitted and other parts broken away for the sake of clearness; and

Figure 3 is a view similar to the upper portion of Figure 1, illustrating a modification.

I have shown my present invention associated with a condenser of the type more fully illustrated and described in my co-pending application. I have shown, for example, a substantially cylindrical or tubular container 10 which may be of any suitable material, and preferably of thin yet strong metal such as sheet aluminum. The container is provided with a bottom wall 11, shown integral therewith, and a top wall 12 which, in the form illustrated, is made of a separate disc having its periphery spun, as at 13, into engagement with the upper edge of the container 10. At its midportion, the container has been shown provided with a partition 14 of conductive material virtually dividing the container into two compartments, in the lower one of which an electrode 15 is arranged and in the upper one of which a separate electrode 16 is arranged. These electrodes may be of any desired character and are usually and preferably in the form of a substantially cylindrical body composed of a spirally wound sheet of aluminum having an electrolytically deposited dielectric coating thereon. I have shown

the electrode 15 mounted upon a supporting rod 17 which extends out of the container through the bottom wall 11; and I have shown the electrode 16 suspended upon a supporting rod or the like 18 which extends upwardly through the top wall 12.

Although the lower electrode, and the method of mounting the condenser upon a platform, has no direct bearing upon my present invention, I will point out briefly that in the form illustrated the bottom wall 11 is provided with a depending, relatively narrow, hollow attachment neck 19 adapted to pass downwardly through a supporting platform 20 or the like and to be engaged beneath the platform by an attachment nut or the like 21. To hold the condenser in the upright position shown, the neck 19 is preferably tapered interiorly, and the lower portion of the rod 17 may be similarly tapered and provided with exterior threads at its lower end adapted to receive a nut or the like 22, the tightening of the nut 22 serving to draw the rod 17 into firm, snug, and liquid-tight association with the neck 19. An electrical connection with the rod 17, and hence with the electrode 15, may be made as at 23, and to insulate the rod from the container washers 24 may be employed together with a sheath or sleeve 25 of insulating material surrounding the lower portion of the rod 17 and extending upwardly into the container for a short distance. This sleeve guards the lower portion of the rod from the likelihood of short-circuit by sediment that may form at the bottom of the container, and the upper end of the sleeve 25 is preferably clamped into position, as at 26. Where the platform 20 is of conductive material, electrical connection is established with the container 10 through this platform, otherwise it may be established at the nut 21 or elsewhere, depending upon requirements.

The upper electrode-supporting rod 18 is preferably threaded exteriorly at its upper end to accommodate a nut 27 or the like which holds the rod in position and in connection with which an electrical connection may be made, as at 28. The rod 18 may be insulated from the container either by making the wall 12 entirely or partially of insulating material, or by the employment of washers such as those shown at 29, together with other insulation surrounding the rod 18 as it passes through the wall 12.

In accordance with my present invention, the rod 18 is provided with an extended collar or flange 30 beneath the top wall 12 and preferably integral with the rod. This flange or disc is provided with an opening 31.

Lying on the upper surface of this flange is a web or sheet 32 of relatively thin diaphragm material, such as elastic rubber or the like; and this element is provided with the central opening 33 adapted to engage

over the rod 18, and is also provided with a relatively small opening or pinhole 34 adapted to align with the opening 31.

Over this I prefer to arrange a clamping member or disc 35 which is of relatively rigid material and preferably, though not necessarily, of insulation. This member has a central opening 36 adapted to accommodate the rod 18, and it has an annular thickened portion 37 around this central opening adapted to fit into the central opening 38 in the top wall 12 to insulate the rod from this wall. The member 35 is also provided with the eccentric, relatively large opening 39 which is adapted to align with the openings 31 and 34.

The top wall 12 is provided with a relatively small aperture 40, also aligned with the other openings, and adapted to serve as a vent for the interior of the container.

When the parts are assembled in the manner shown most clearly in Figure 1, the tightening of the nut 27 will cause the diaphragm member 32 to be securely clamped between the flange 30 and the member 35, and the latter member will also be forced firmly into engagement with the under-surface of the top wall 12 so that the opening 39 will virtually provide what may be termed a chamber beneath the top wall 12, and, more especially, beneath the aperture 40.

That portion of the web 32 which lies in alignment with the opening 39 constitutes a movable or distensible diaphragm which serves as a valve member in the manner presently to be described, and, with respect to the chamber constituted of the opening 39, this diaphragm serves as a bottom wall.

The opening or pinhole 34 is normally closed due to the natural resilience of the material of the diaphragm. And under normal conditions it is therefore obvious that the interior of the container is sealed by this diaphragm, no gases, and, obviously, no liquid, being capable of escape through the aperture 40 in the top wall 12. The handling, packing, and shipment of the condenser is therefore totally devoid of any likelihood of leakage or damage.

When the pressure of the gases within the space 41, overlying the level of the electrolyte 42, exceeds a predetermined maximum the diaphragm is distended or ballooned upwardly into the opening 39, and this causes the pinhole 34 momentarily to enlarge to permit escape of gases into the opening or chamber 39 and thence out of the container through the aperture or vent 40. Immediately after the pressure has been relieved in this manner, the diaphragm resumes its normal retracted position and serves again to seal to vent 40.

As a result, the container is efficiently and satisfactorily vented for the purposes hereinbefore referred to, while at the same time

the interior of the container is normally sealed, and there are no protuberances or similar projections on the exterior of the container.

Obviously, the construction may be altered in a variety of ways to meet differing requirements. The flange 30 may, if desired be a separate element and need not be integral with the rod 18. The material of the diaphragm 32 may be of any suitable character and it need not necessarily be composed of resilient material provided with a pinhole. For example since the diaphragm serves as a valve instrumentality for opening the vent only at predetermined times the movement of the diaphragm, whether such movement be a distention or not, might be employed to initiate the operation of, or actuate, an auxiliary valve member or its equivalent for fulfilling the same function. Or, the diaphragm illustrated, which is the preferred type of valve member, might be replaced by any other suitable type of valve wherein a movable portion thereof is normally retracted to keep the vent closed and is adapted to be moved out of its normal position for the purpose of unsealing the vent.

Furthermore, the upper clamping member 35 may be entirely dispensed with, if desired, and the opening 39 may be provided in the top wall 12 in place of the relatively small aperture 40. In such an event, the distention of a diaphragm of the character herein illustrated would take place upwardly into and through such opening in the top wall 12, and, obviously, under such an arrangement, the diaphragm would have to be clamped directly between the flange 30 or its equivalent and the top wall 12 itself.

Furthermore, although I have shown the various elements of my valve arrangement mounted upon and supported by the electrode rod 18, it will be understood that this arrangement is not essential, and the several operative portions of the venting device may be supported either from the top wall 12 or by other suitable means within the container.

In Figure 3, for example, I have shown a construction wherein there is no electrode rod, Figure 3 representing the upper portion of an electrolytic condenser or the like wherein only a single or lower electrode is immersed in the electrolyte. In this construction, a container 43 has a top wall 44 provided with the aperture or vent 45. The flange 30 of Figure 2 is replaced by a supporting element or disc 46 which is carried by a pin or stud 47 riveted or eyeletted or similarly attached to the top wall 44. The member 46 has the opening 48 and carries the diaphragm member 49 with the pinhole 50 therein. A clamping member 51 is mounted on top of the diaphragm and is held in clamped position between the diaphragm and the top wall 44.

The operation of the device of Figure 3 will be obvious from the description hereinbefore given, and serves to show the possibility of mounting a venting arrangement 5 within a container of the present character independently of any electrode-supporting rod which extends through the top wall.

The possible variations in structure previously referred to may be applied with equal 10 facility to the construction of Figure 3.

Furthermore, although I have herein illustrated and described my invention as it applies to an electrolytic condenser, it will be understood that many of the phases of my 15 invention are not restricted to a device of this character and may find wide applicability in other analogous or non-analogous arts, and, in fact, in any case where venting of a container is desired for similar purposes.

20 In general, it will be obvious that changes in the details herein described and illustrated for the purpose of explaining the nature of my invention may be made by those skilled in the art without departing from the spirit and scope of the invention as expressed in the 25 appended claims. It is therefore intended that these details be interpreted as illustrative, and not in a limiting sense.

Having thus described my invention and 30 illustrated its use, what I claim as new and desire to secure by Letters Patent is—

1. In an electrolytic condenser, an electrolyte container having a wall provided with an aperture adapted to serve as a vent, a rubber diaphragm having a perforation therein and positioned underneath said vent for normally sealing the latter, said diaphragm being adapted to distend and enlarge said perforation and thereby unseal said vent under excessive 35 pressure conditions within the container, and a pair of clamping members engaging said diaphragm on opposite sides thereof to hold the same in position, the inner of said members having a stem mounted in said container wall.

2. In an electrolytic condenser, a substantially cylindrical electrolyte container having an end wall provided with an aperture adapted to serve as a vent, an electrode-supporting rod mounted in said wall alongside of said vent, and means within the container and carried by said rod for normally sealing said vent and adapted to unseal said vent under excessive pressure conditions within the container.

3. In an electrolytic condenser, a substantially cylindrical electrolyte container having an end wall provided with an aperture adapted to serve as a vent, an electrode-supporting rod mounted in said wall alongside of said vent, and a valve within the container and carried by said rod for normally sealing said vent, said valve being adapted to unseal said vent only under excessive pressure conditions within the container.

4. In an electrolytic condenser, a substantially cylindrical electrolyte container having an end wall provided with an aperture adapted to serve as a vent, an electrode-supporting rod mounted in said wall alongside of said vent, and a rubber diaphragm with a pinhole therein carried by said rod and arranged underneath said vent for normally sealing the latter, said diaphragm being adapted to distend and enlarge said pinhole, thereby unsealing said vent under excessive pressure conditions within the container.

5. In an electrolytic condenser, a substantially cylindrical electrolyte container having an end wall provided with an aperture adapted to serve as a vent, an electrode-supporting rod mounted in said wall alongside of said vent, a flange mounted on said rod beneath said end wall and provided with an opening aligned with said vent, a relatively thin, distensible diaphragm on the outer surface of said flange, said diaphragm having a pinhole over said opening, and a clamping disc snugly fitted between said end wall and said diaphragm, said disc having an opening aligned with said vent and pinhole, whereby the diaphragm will normally seal said vent and whereby distention of the diaphragm into said disc opening under excessive pressure conditions within the container will enlarge said pinhole and thereby unseal said vent.

6. In an electrolytic condenser, an electrolyte container having a wall provided with an aperture adapted to serve as a vent, a distensible diaphragm having a perforation therein and positioned underneath said vent for normally sealing the latter, said diaphragm being adapted to distend to unseal said vent under excessive pressure conditions within the container, and means engaging said diaphragm peripherally to hold the same in position, said means comprising a clamping member having a stem mounted in said container wall.

In witness whereof I have signed this specification this 26 day of February, 1931.

HAROLD I. DANZIGER.
